UNITED STATES PATENT OFFICE.

WILLIAM B. MASON, OF BOSTON, MASSACHUSETTS, ASSIGNOR TO THE MASON
REGULATOR COMPANY, OF SACO, MAINE, A CORPORATION OF MAINE.

APPARATUS FOR MAINTAINING UNIFORM PRESSURE IN DRIERS.

No. 858,089.

Specification of Letters Patent.

Patented June 25, 1907.

Application filed May 17, 1906. Serial No. 817,329.

To all whom it may concern:

Be it known that I, WILLIAM B. MASON, a citizen of the United States, residing at Boston, county of Suffolk, and Commonwealth of Massachusetts, have invented a certain new and useful Improvement in Apparatus for Maintaining Uniform Pressure in Driers, of which the following is a specification, reference being had therein to the accompanying drawings.

My invention has for its object to provide a device which shall be adapted to maintain a constant pressure in a chamber such, for instance, as the chamber of a paper drier, although the main source of supply for the pressure is variable, the other or auxiliary source of supply being at a pressure relatively higher than the main source of supply.

This invention is adapted particularly for use where it is desired to maintain a constant pressure in a chamber which is supplied with steam from the exhaust pipe of a steam engine, additional pressure being obtained when necessary from the boiler.

My present invention is also especially adapted for use in connection with small steam pipes which can be readily carried to any convenient point so that the various pieces of mechanism which embody my invention may be conveniently grouped upon a single panel or board.

The invention furnishes a simple and compact mechanism and affords a thoroughly reliable means for accomplishing the result desired, namely, the maintenance of a substantially constant pressure in the chamber. It is also exceedingly economical in steam because it utilizes the exhaust steam to the fullest extent possible.

The invention will be fully understood from the following specification taken in connection with the accompanying drawings, and the novel features thereof are pointed out and clearly defined in the claims at the close of the specification.

In the drawings,—the figure is a diagrammatic view of the mechanism embodying my invention.

Referring to the drawings, at A is indicated the variable source of steam supply, as, for instance, the exhaust pipe from the engine. The exhaust pipe A is connected by the small pipes B with the paper driers or other chambers in which it is desired that constant pres-

sure be maintained. At C is indicated a vent to the atmosphere connected to the exhaust pipe A and controlled by the vent valve D which is mounted upon the panel or board E. The exhaust pipe A is also connected with a boiler pipe S through which the steam or other fluid under high pressure is admitted to the chamber when required. The flow through this pipe is controlled by the high pressure valve F also mounted upon the panel E.

At G there is shown a pressure weighing device connected by the pipe H with the chamber supply pipe and movable in response to changes in pressure in the said chamber. This pressure weighing device may be of any suitable form, but in practice I find it convenient to use the device shown and described in Letters Patent No. 561,600, granted to me July 9, 1896. The said pressure weighing device G is connected as shown at R to a source of water supply under pressure, such, for instance, as a city water main, and operates when the pressure in the chamber rises above a predetermined point to cause the wheel J to rotate and to wind the chain or flexible connection K upon it. The said chain K passes over various pulleys L, and is attached to one end of a lever M pivoted at O to the panel E. The chain or flexible connection K is furnished with a heavy counterweight N which serves to keep it taut when it is unwound from the pulley J.

When the exhaust pipe A is furnishing too much steam or steam at too high a pressure to the chamber, it is necessary to open the vent valve D to allow a portion of the steam to escape to the atmosphere, and to lower the pressure in the chamber thereby. On the other hand, if the steam furnished by the exhaust pipe A is insufficient to maintain the desired pressure in the chamber, it is necessary to open the high pressure valve F and allow steam from the boiler or other source of high pressure to flow into the chamber until the pressure in the chamber has risen to the predetermined point, when the high pressure valve should be closed. When the pressure in the chamber rises above the predetermined point, and causes the pressure weighing device G to operate to wind the chain K up on the wheel J, the counterweight N and the right hand arm of the main or operating lever M are raised,

thus causing the left hand end of the said lever M to be correspondingly depressed. The left hand end of the lever M is connected by means of a pivoted connecting rod 11 with the high pressure valve lever 12, the said pivoted rod 11 being screw threaded and provided with a movable tappet 13 which is adjustable vertically on the said pivoted connecting rod 11. The high pressure valve lever 12 is pivoted at 131 to a movable fulcrum 14 fixed to the casing of the valve F, and is guided in a slot in a fixed arm 141, also supported on the said casing of the valve F. The valve spindle 16 is pivotally connected to the said valve lever 12 between the fulcrum and the fixed arm 141, so that the said valve is closed by the downward movement of the high pressure valve lever 12 and opened by its upward movement.

20 The vent valve D is similarly provided with a valve lever 16 connected by a second pivoted connecting rod 17 with the operating lever M, said pivoted connecting rod also being furnished with an adjustable tappet 18.

25 The vent valve lever 16 is pivoted to a movable fulcrum 19, which is nearer the point of the application of the lever than is the valve spindle 20 which is operated thereby. A slotted guiding arm 21 is also provided.

30 Both valve levers 12 and 16 are provided with counterweights 22 and 23 which are adjustable longitudinally of the said valve levers, and which tend to keep the said levers in contact with the tappets.

35 When the right hand end of the main operating lever M has been raised by the rise in pressure of the chamber above the predetermined point, it allows the high pressure valve lever 12 to fall and thus closes the high pressure valve F, thereby preventing the further admission of high pressure steam into the drying chamber. When the valve lever 12 moves downwardly far enough to close the valve F, it engages the bottom of

40 the slot in the arm 141 fixed to the casing of the valve F which prevents the valve lever 12 from moving further, but allows the connecting rod 11 by reason of the loose connection between it and the valve lever to

45 continue its movement irrespective of the valve lever 12, the valve F remaining closed until the tappet 13 is brought in contact again with the under side of the valve lever 12, as will be hereinafter described. If closing the supply of high pressure steam from the source of supply is still insufficient to cause the pressure in the drier or chamber to fall to the desired point, or to put the matter in a different way, if the steam from

50 the exhaust pipe A is more than sufficient to maintain the predetermined pressure in the chamber, the right hand end of the lever M continues its upward movement, causing the left hand end thereof to be depressed and

55 the tappet 18 thereon to contact with the

lever 16, thus depressing the said vent valve lever and opening the vent valve D to reduce the pressure in the chamber as is necessary.

When the pressure in the chamber falls, the reverse action takes place. The pressure weighing device allows the counterweight N to unwind the chain or flexible connection K from the wheel J and to depress the right hand end of the lever M, thus allowing the vent valve to rise until the end upon which its weight 23 is located comes in contact with the bottom of its slot. If this change is not sufficient to raise the pressure in the chamber to the required amount, the movement of the lever M continues, the tappet 13 comes in contact with the high pressure valve lever 12 and the high pressure valve F is again opened to admit steam in the chamber.

Under ordinary conditions, I find that the steam from the exhaust pipe is sufficient to maintain the desired pressure in the chamber and so long as this is the case, it is only necessary for the vent valve to be opened and closed as required to reduce the pressure in the chamber to maintain the predetermined pressure at a practically constant point in the chamber. If, for any reason, the exhaust pipe should fail to supply the requisite amount of steam, the device will then open the high pressure valve, as has been previously described. At other times, the high pressure valve remains inactive.

While I have described my present invention as applied to a chamber supplied with steam from the exhaust pipe of an engine, and having an auxiliary supply from a boiler, it will be understood that my device is equally applicable to any place where it is desired to maintain a constant pressure from a source of supply which is variable assisted by an auxiliary supply at a high pressure.

I claim as my invention:

1. Controlling mechanism for maintaining a predetermined pressure in a chamber supplied from two sources, the main source of which is variable, and the auxiliary source of which is of relatively high pressure, which comprises a vent valve and a high pressure valve, a main operating lever, whose movement in one direction acts to close the high pressure valve and open the vent valve and whose movement in the other direction acts to close the vent valve and open the high pressure supply valve, and a pressure weighing device responsive to changes in pressure in the chamber and operating to move the said lever.

2. Controlling mechanism for maintaining a predetermined pressure in a chamber supplied from two sources, the main source of which is variable, the auxiliary source of which is of relatively high pressure, which comprises a vent valve, a high pressure valve, a main operating lever, connections

between the main operating lever and the said two valves, and a pressure weighing device responsive to changes in pressure in the chamber, and operating to move the said 5 main operating lever in one direction to close the vent valve and open the high pressure valve and in the other direction to close the high pressure valve and open the vent valve.

3. Controlling mechanism for maintaining a predetermined pressure in a chamber supplied from two sources, the main source of which is variable, the auxiliary source of which is of relatively high pressure, which comprises a vent valve and a valve lever therefor, a high pressure valve and valve lever therefor, a main operating lever, connections between the main operating lever and the said two valve levers, and a pressure weighing device responsive to changes in 15 pressure in the chamber and operating to move the said main operating lever in one direction to close the vent valve and open the high pressure valve and in the other direction to close the high pressure valve and open the 20 vent valve.

25 4. Controlling mechanism for maintain-

ing a predetermined pressure in a chamber supplied from two sources, the main source of which is variable, and the auxiliary source of which is of relatively high pressure, which 30 comprises a vent valve and a valve lever therefor, a high pressure valve and a lever therefor, rests for the said valve levers when the valves are closed, a main operating lever, intermediate connections between the said 35 main operating lever and the said valve levers, tappets on the said intermediate connections alternately contacting with the said valve levers, and a pressure weighing device responsive to changes in pressure in the chamber and operating to move the said main operating lever in one direction to close the vent valve and open the high pressure valve, and in the other direction to close the high 40 pressure valve and open the vent valve. 45

In testimony whereof I affix my signature, in presence of two witnesses.
